UNITED STATES PATENT OFFICE.

WILLIAM N. WHITELY, OF SPRINGFIELD, OHIO.

GRAIN-BINDING HARVESTER.

SPECIFICATION forming part of Letters Patent No. 737,986, dated September 1, 1903.

Application filed May 27, 1901. Serial No. 62,149. (No model.)

To all whom it may concern:

Be it known that I, WILLIAM N. WHITELY, a citizen of the United States, residing at No. 153 East High street, Springfield, in the county of Clark and State of Ohio, have invented certain new and useful Improvements in Grain-Binding Harvesters; and I do declare the following to be a full, clear, and exact description of the invention, such as will enable others skilled in the art to which it appertains to make and use the same, reference being had to the accompanying drawings, and to the letters of reference marked thereon, which form a part of this specification.

My invention relates to harvesting-machines; and my improvement consists chiefly in a new system of cog-toothed gearing for operating the lower-elevator belt, the upper-elevator belt, the reeling mechanism, the grain-rake mechanism located at the inner end of the cutting apparatus, the butt-adjuster mechanism located over the binder-deck, and the stripping-roller located between the upper end of the lower elevator and the binder-deck.

Three gears supported upon the upper rear end of the lower elevator and driven by the upper-roller shaft of the lower elevator to space the right distance and rotate the stripping-roller in the proper direction have been used. Sometimes a short sprocket-chain driven from a sprocket-wheel located on the upper-roller shaft of the lower elevator running onto a similar sprocket-wheel on the stripping-roller is used. These devices were cumbersome and complicated and added additional parts to the construction of the machine.

One object of my invention is to simplify the construction of harvesting-machines by using fewer parts to accomplish the desired object. I attain this object by the mechanism shown in the accompanying drawings, in which—

Figure 1 is a front elevation of a harvesting-machine, showing the location of the cog-toothed gearing system, the grain-rake, reel, and butt-adjuster mechanism. Fig. 2 is a rear elevation of so much of a harvesting-machine as will show the method of driving the horizontal grain-conveying belt, the upper roller of the lower-elevator belt, and the

binder mechanism. Fig. 3 is a detail of the single-piece metallic box and system of cog-toothed gears located thereon for driving the three rollers, reel-driving shaft, and grain-rake shaft. Fig. 4 is a detail plan of the three cog-toothed gears. Fig. 5 is a detail of the combined spur-wheel and bevel-pinion for the stripping-roller shaft. Fig. 6 is an elevation of the single-piece metallic box.

Similar letters of reference indicate like parts in the several views.

In Fig. 1, a^1 indicates the cutting apparatus; a^2 , the grain-divider; a^3 , the horizontal grain-conveying belt; a^4 , the reel; a^5 , the elevator; a^6 , the binder-deck; a^7 , the grain-rake located at the inner front end of the cutting apparatus; a^8 , a swinging link connection between the grain-rake and elevator-framing; a^9 , the grain-rake driving-crank; a^{10} , the binder mechanism.

In Fig. 2 is shown a link belt b , driven by the sprocket-wheel b^1 and running over the tightener sprocket-wheel b^2 and around the sprocket-wheel b^3 , which gives motion to the horizontal grain-conveying belt a^3 , thence upward to the sprocket-wheel b^4 , secured to the rear end of the upper-roller shaft b^5 of the lower elevator, thence to the sprocket-wheel b^6 , which communicates motion to the binder mechanism.

At the top of the front elevator side a^5 is secured a single-piece metallic box c , which forms a support for the front end of the elevator roller-shaft b^5 . To the forward end of said roller-shaft is secured a combined cogged toothed spur-wheel and bevel-pinion c' , which engages the double-faced cogged toothed spur-wheel c^2 , rigidly secured to the forward end of the upper-roller shaft c^3 of the upper elevator, the forward end of said roller-shaft mounted in and supported by the single-piece metallic box c . The forward end of the stripping-roller shaft c^4 is also mounted in and supported by the single-piece metallic box c . To the forward end of said stripping-roller shaft is secured the combined cog-toothed spur gear-wheel and bevel-pinion c^5 , which engages the double-faced cog-toothed spur gear-wheel c^2 , secured to the forward end of said upper-roller shaft c^3 of the upper elevator, and as the link belt b in its movement rotates the toothed sprocket-wheel b^4 , located

on the rearward end of the roller-shaft b^5 , motion is transmitted to the cog-toothed spur gear-wheel c' , which rotates the cog-toothed spur gear-wheel c^2 , located on the upper-
5 roller shaft c^3 of the upper elevator. The cog-toothed spur-gear c^2 being double-faced engages with and communicates motion to the cog-toothed spur-wheel c^5 , secured to the forward end of the stripping-roller shaft, which
10 completes the driving mechanism for the two upper rollers, for the upper and lower elevators, and the stripping-roller.

The cog-toothed spur gear-wheel c' has formed thereon a cog-toothed bevel-pinion d ,
15 (the same as the cog-toothed spur gear-wheel c^5 shown in Fig. 5,) which engages the cog-toothed bevel-wheel d' , secured to the upper end of the reel and grain-rake rotary driving-shaft d^2 , Figs. 1 to 3. Said shaft is
20 held in proper working position by the bearing d^3 , formed upon and made a part of the single-piece metallic box c , thus completing the reel driving and grain-rake mechanism.

The lower end of the reel and grain-rake
25 rotary driving-shaft d^2 is universally pivotally connected to the toothed sprocket-wheel c^6 , secured to the grain-rake driving cranked shaft a^9 , communicating motion to the reel, said shaft passing through the bracket d^{10} ,
30 which is secured to the elevator-framing, said bracket forming a support for the reel-post d^{11} and the grain-rake driving cranked shaft a^9 . To the grainward end of the cranked shaft a^9 is pivotally secured the grain-rake a^7 .
35 To the upper end of said grain-rake is pivotally secured a swinging link a^8 , the rearward end of said link pivotally connected to the elevator-framing.

The cog-toothed spur gear-wheel c^5 (shown
40 in Fig. 5) is also provided with a cog-toothed bevel-pinion d^4 , located thereon, which engages with and rotates the bevel-wheel d^5 , secured to the lower end of the butt-adjuster driving-shaft d^6 , said shaft passing upward
45 through the bearing d^7 , which is formed upon the single-piece metallic box c . To the upper end of said shaft d^6 is secured a bevel-pinion d^8 , which engages with and rotates the butt-adjuster crank-shaft driving-gear d^9 ,
50 Fig. 1, thereby transmitting motion to the grain-butt-adjuster mechanism d^{12} .

At the extreme front end of the upper-roller shaft of the lower elevator is located a combined cog-toothed spur-wheel and bevel-pinion c' , the spur cog-toothed portion of said wheel engaging with and driving a cog-toothed spur-wheel c^2 , having a double-width face secured to the upper-roller shaft of the upper elevator, thereby transmitting motion to the
55 upper-roller shaft of the upper elevator, rotating the upper roller of the upper elevator in the right direction. The bevel cog-toothed portion of said combined cog-toothed gear spur-wheel and bevel-pinion c' engages a bevel-wheel d' , located on the upper end of a rotary driving-shaft, which transmits motion to the reeling mechanism and grain-rake
60

mechanism located at the inner front end of the cutting apparatus.

The front end of the stripping-roller shaft c^4 70 is also provided with a combined cog-toothed spur-wheel and bevel-pinion c^5 , the spur cog-toothed portion of said wheel engaging the double-faced cog-toothed spur-wheel c^2 , secured upon the upper-roller shaft of the upper elevator, and deriving its motion from the same and communicating motion to the stripping-roller c^6 and rotating said roller in the right direction and spacing the several rollers at the proper distance apart, the bevel 75 cog-toothed portion of said spur-wheel and bevel-pinion c^5 , engaging a cog-toothed bevel-wheel d^5 , secured to the lower end of the butt-adjuster shaft d^6 , thereby communicating motion to the grain-butt-adjuster mechanism d^{12} , 80 located over the forward end of the binder-deck.
85

It will be observed that by this construction there are three centers for the two elevator-shafts and the stripping-roller shaft, 90 said shafts having bearings at their forward ends in a single-piece metallic box c , secured to the front end of the elevator-framing at its upper end. The roller-shafts being long and provided with fixed centers, they are easily 95 kept in proper working relation to each other, and no intermediate gears or chain-tightening mechanism is required to give the three roller-shafts the proper motion and rotate them in the right direction.
90

By this cog-toothed gear system a lighter, cheaper, and a more convenient and compact construction is attained for driving the upper rollers of the upper and lower elevators, the stripping-roller, the grain-rake, the butt- 105 adjuster, and reeling mechanism.

What I claim, and desire to secure by Letters Patent, is—

1. In a grain-binding harvester, in combination, a pair of grain-elevator belts, a binder mechanism, a binder-deck between the elevator and binder mechanism, a stripping-roller located between the upper end of the lower elevator and the binder-deck, its upper face about the plane of the binder-deck forming a moving bridge between the upper end of the lower-elevator belt and the binder-deck, a butt-adjuster mechanism located over the forward part of the binder-deck and deriving its motion from the forward end of one of said grain-moving rollers, a reeling mechanism, a driving-chain located on the rearward part of the machine, a sprocket-wheel mounted upon the rear end of the upper-roller shaft of the lower-elevator belt and driven by said chain 110 communicating motion to the elevator-belts, reeling mechanism, stripping-roller and butt-adjuster; a double cog-toothed gear-wheel located upon the forward end of the upper-roller shaft of the lower elevator, one series 115 of cog-teeth of said double cog-toothed gear-wheel, communicating motion to the reeling mechanism, a cog-toothed gear-wheel mounted upon the forward end of the upper-roller 120

120

125

130

135

shaft of the upper-elevator belt and intermeshing with the other series of teeth of said double cog-toothed gear-wheel, a cog-toothed gear-wheel located upon the forward end of the stripping-roller shaft and directly intermeshing with the cog-toothed gear-wheel located upon the forward end of the upper-roller shaft of the upper elevator, rotating said stripping-roller shaft in an opposite direction.

2. In a grain-binding harvester, in combination, a horizontal grain-conveying belt, a pair of grain-elevating belts, a binder mechanism, a binder-deck between the elevator and binder mechanism, a stripping-roller located between the upper end of the lower elevator and binder-deck, a main driving sprocket-wheel located upon the rearward portion of the harvester part of the machine, one continuous drive-chain driven by said sprocket-wheel and located on the rearward portion of the machine, which chain directly operates the horizontal grain-conveying belt, the binder mechanism and lower-elevator belt; the upper-roller shaft of said lower-elevator belt extending forward to the front end of the machine and having a double cog-toothed gear-wheel secured to its forward end, a vertically-inclined rotary driving-shaft for the reel and grain-rake mechanism secured to the forward portion of the elevator, a cog-toothed gear-wheel located on the upper end of said vertically-inclined rotary driving-shaft and directly intermeshing with one series of cog-teeth of said double cog-toothed gear-wheel located on the forward end of said upper-roller shaft of the lower elevator, the other series of teeth of said double cog-toothed gear-wheel and located on the forward end of the upper-roller shaft of the upper elevator rotating said roller-shaft in the opposite direction, a cog-toothed gear-wheel directly meshing with said wheel on the forward end of the upper shaft of the upper elevator and secured to the forward end of the stripping-roller shaft and rotating said stripping-roller in the same direction as the upper roller of the lower elevator.

3. In a grain-binding harvester, in combination, a horizontal grain-conveying belt, a pair of grain-elevating belts, a binder mechanism, a binder-deck between the elevator and binder mechanism, a stripping-roller located between the upper end of the lower elevator and binder-deck, a reeling mechanism, a grain-rake mechanism located at the inner front corner of the cutting apparatus, a main driving sprocket-wheel located upon the rearward portion of the harvester part of the machine, one continuous drive-chain located on the rearward portion of the machine and driven by said sprocket-wheel, which chain directly communicates motion to the horizontal grain-conveying belt, the binder mechanism and lower-elevator belt;

the upper-roller shaft of said lower-elevator belt extending forward to the front part of the machine and having a double cog-toothed gear-wheel secured to its forward end, a vertically-inclined rotary driving-shaft secured to the forward portion of the elevator for the reel and grain-rake mechanism, a cog-toothed gear-wheel located on the upper end of said vertically-inclined shaft and directly intermeshing with one series of cog-teeth of said double cog-toothed gear-wheel located on the forward end of said upper-roller shaft of the lower elevator, a cog-toothed gear-wheel mounted upon said stripping-roller shaft and directly intermeshing with the cog-toothed gear-wheel located upon the forward end of the upper-roller shaft of the upper elevator to rotate said stripping-roller in the same direction as the upper roller of the lower elevator.

4. In a grain-binding harvester, in combination, a horizontal grain-conveying belt, a pair of grain-elevating belts, a binder mechanism, a binder-deck between the elevator and binder mechanism, a stripping-roller located between the upper end of the lower elevator and binder-deck, a reeling mechanism, a butt-adjuster mechanism located and operating over the forward end of the binder-deck, a main driving sprocket-wheel located on the rearward part of the harvester, one continuous drive-chain driven by said sprocket-wheel and located on the rearward portion of the machine, which chain directly communicates motion to the horizontal grain-conveying belt, the binder mechanism and lower-elevator belt; the upper-roller shaft of said lower-elevator belt extending forward to the front of the machine and having a double cog-toothed gear-wheel secured to its forward end, a vertically-inclined rotary driving-shaft for the reel secured to the forward portion of the elevator, a grain-rake mechanism connected to and operated by said vertically-inclined rotary driving-shaft, a cog-toothed gear-wheel located on the upper end of said vertically-inclined shaft and directly intermeshing with one series of cog-teeth of said double cog-toothed gear-wheel located on the forward end of said upper-roller shaft of the lower elevator and communicating motion to the reeling mechanism, a cog-toothed gear-wheel located on the forward end of the upper-roller shaft of the upper elevator and directly intermeshing with the other series of teeth of said double cog-toothed gear-wheel rotating said roller-shaft in an opposite direction, a double cog-toothed gear-wheel located on the forward end of said stripping-roller shaft and directly meshing with said

wheel located on the forward end of the upper shaft of the upper elevator, rotating said stripping-roller in the same direction as the upper-roller shaft of the lower elevator, a 5 cog-toothed gear-wheel located on the lower end of said vertically-inclined rotary driving-shaft and intermeshing with the other series of teeth of said double cog-toothed gear-wheel to drive the butt-adjuster mechanism.

10 5. In a grain-binding harvester, in combination, a horizontal grain-conveying belt, a pair of grain-elevating belts, a binder mechanism, a binder-deck between the elevator and binder mechanism, a stripping-roller located between the upper end of the lower elevator and binder-deck, a reeling mechanism, a grain-rake mechanism located at the inner front corner of the cutting apparatus, a butt-adjuster mechanism located over the forward 15 end of the binder-deck, a main driving sprocket-wheel located on the rearward portion of the harvester part of the machine, one continuous drive-chain located on the rearward part of the machine and driven by said sprocket-wheel, which chain communicates 20 motion to the horizontal grain-conveying belt, binder mechanism and lower-elevator belt; the upper-roller shaft of said lower-elevator belt extending forward to the front of the machine and having a double cog-toothed gear-wheel secured to the forward end of said shaft, a vertically-inclined rotary shaft secured to the forward portion of the elevator, a cog-toothed gear-wheel secured to the upper end of said shaft and directly intermeshing 25 with one series of cog-teeth of said double cog-toothed gear-wheel secured to the forward end of the upper-roller shaft of the lower elevator, the reeling and grain-rake mechanism being operated by said vertically-inclined rotary driving-shaft, a cog-toothed gear-wheel directly intermeshing with the other series of teeth of said double cog-toothed gear-wheel and located on the forward end of the upper-30 roller shaft of the upper elevator rotating said upper-roller shaft in an opposite direction, a double cog-toothed gear-wheel directly intermeshing with said wheel on the forward end of the upper-roller shaft of the upper elevator and secured to the forward end of said stripping-roller shaft, rotating said stripping-35 roller in the same direction as the upper roller of the lower elevator, a vertically-inclined revolving shaft secured to the forward portion of the elevator, a cog-toothed gear-wheel directly intermeshing with the other series of teeth of said double cog-toothed gear-wheel on said stripping-roller shaft and secured to the lower end of said vertically-inclined revolving shaft to drive said butt-adjuster mechanism.

40 6. In a grain-binding harvester, in combination, a horizontal grain-conveying belt, a pair of grain-elevating belts, a stripping-roller, a grain-rake mechanism located at the inner front corner of the cutting apparatus, a main driving sprocket-wheel located on the

rearward portion of the harvester part of the machine, one continuous drive-chain driven by said sprocket-wheel and located on the 70 rearward portion of the machine, which chain directly operates the horizontal grain-conveying belt, the grain-elevating belts and binder mechanism; the upper-roller shaft of said lower elevator extending forward to the front 75 of the machine and having a double cog-toothed gear-wheel secured to its forward end, a vertically-inclined rotary driving-shaft secured to the forward portion of the elevator and communicating motion to said grain-rake 80 mechanism, a cog-toothed gear-wheel secured to the upper end of said vertically-inclined rotary driving-shaft and directly intermeshing with one series of cog-teeth of said double cog-toothed gear-wheel secured to the forward end of said upper-roller shaft of the lower elevator, a grain-rake and reel-driving crank, its stubbleward end universally pivoted 85 connected to said vertically-inclined rotary driving-shaft. 90

7. In a grain-binding harvester, in combination, a horizontal grain-conveying belt, a pair of grain-elevating belts, a binder mechanism, a binder-deck between the elevator and binder mechanism, a stripping-roller located between the upper end of the lower elevator and binder-deck, a reeling mechanism, a butt-adjuster mechanism located over the forward portion of the binder-deck to move the butts of the grain binderward, a main 95 driving sprocket-wheel located on the rearward portion of the harvester part of the machine, one continuous drive-chain directly driven by said sprocket-wheel and located on the rearward portion of the machine, which 100 chain directly operates the horizontal grain-conveying belt, the binder mechanism and lower-elevator belt; the upper-roller shaft of the lower-elevator belt extending forward to the front of the machine and having a double 105 cog-toothed gear-wheel secured to its forward end, one series of cog-teeth of said double cog-toothed gear-wheel directly intermeshing with a cog-toothed gear-wheel located upon the forward end of the upper-roller shaft of 110 the upper elevator, rotating said shaft in an opposite direction from that of said upper-roller shaft of the lower elevator, a rotary 115 vertically-inclined driving-shaft secured to the forward portion of the elevator, a cog-toothed gear-wheel directly intermeshing with the other series of teeth of said double cog-toothed gear-wheel and located upon the upper end of said rotary vertically-inclined driving-shaft to communicate motion to the 120 reel mechanism, a double cog-toothed gear-wheel directly meshing with said cog-toothed gear-wheel on the upper-roller shaft of the upper elevator and secured to the forward 125 end of said stripping-roller shaft, rotating said stripping-roller in the same direction as the upper roller of the lower elevator, a vertically-inclined rotary driving-shaft secured to the forward portion of the elevator, 130

5 a cog-toothed gear-wheel directly intermeshing with the other series of teeth of said double cog-toothed gear-wheel and located on the lower end of said vertically-inclined rotary driving-shaft communicating motion to said butt-adjuster mechanism.

8. In a grain-binding harvester, in combination a pair of grain-elevating belts, a binder mechanism, a binder-deck between the elevator and binder mechanism, a stripping-roller located between the upper end of the lower elevator and binder-deck, a reeling mechanism, a grain-rake mechanism located at the inner front corner of the cutting apparatus; the upper-roller shaft of said lower-elevator belt extending forward to the front of the machine and having a double cog-toothed gear-wheel secured to its forward end, a vertically-inclined rotary driving-shaft secured to the forward portion of the elevator to communicate motion to the reeling and grain-rake mechanism, a cog-toothed gear-wheel secured to the upper end of said rotary driving-shaft and directly intermeshing with one series of cog-teeth of said double cog-toothed gear-wheel secured to the forward end of said upper-roller shaft of the lower elevator, a grain-rake and reel-driving crank, its grainward end pivotally connected to said grain-rake mechanism, its stubbleward end universally pivotally connected to said vertically-inclined rotary driving-shaft, a cog-toothed gear-wheel directly intermeshing with the other series of teeth of said double cog-toothed gear-wheel and located on the forward end of the upper-roller shaft of the upper elevator, rotating said roller-shaft in an opposite direction, a cog-toothed gear-wheel directly intermeshing with said wheel on the forward end of the upper shaft of the upper elevator and secured to the forward end of said stripping-roller shaft, rotating said stripping-roller in the same direction as the upper-roller shaft of the lower elevator.

45 9. In a grain-binding harvester, in combination, a pair of grain-elevating belts, a binder

mechanism, a binder-deck between the elevator and binder mechanism, a stripping-roller located between the upper end of the lower elevator and binder-deck, a grain-reeling mechanism, a butt-adjuster mechanism located and operating over the forward end of the binder-deck to move the butts of the grain binderward; the upper-roller shaft of said lower-elevator belt extending forward to the front part of the machine and having a double cog-toothed gear-wheel secured to its forward end, a cog-toothed gear-wheel located on the forward end of the upper-roller shaft of the upper elevator, and directly intermeshing with one series of cog-teeth of said double cog-toothed gear-wheel secured to the forward end of the upper-roller shaft of the lower elevator, communicating motion to said shaft and rotating same in an opposite direction from said upper roller of the lower elevator, a vertically-inclined rotary shaft secured to the forward portion of the elevator, a cog-toothed gear-wheel directly intermeshing with the other series of teeth of said double cog-toothed gear-wheel and located on the upper end of said vertically-inclined rotary shaft to communicate motion to the grain-reeling mechanism, a cog-toothed gear-wheel directly meshing with said wheel on the forward end of the upper shaft of the upper elevator and secured to the forward end of said stripping-roller shaft, rotating said stripping-roller in the same direction as the upper roller of the lower elevator, said mechanism forming a three-center cog-toothed gear system located on the forward upper portion of the elevators and operated without the necessity of the intervention of other gearing on other centers to produce the desired motion to the parts referred to.

In testimony whereof I affix my signature in presence of two witnesses.

WILLIAM N. WHITELY.
